UNITED STATES PATENT OFFICE.

DAVID J. DORSEY, OF BATON ROUGE, LOUISIANA.

SHADE AND CURTAIN HANGER.

1,330,243.

Specification of Letters Patent.

Patented Feb. 10, 1920.

Application filed August 13, 1919. Serial No. 317,160.

To all whom it may concern:

Be it known that I, DAVID J. DORSEY, a citizen of the United States, residing at Baton Rouge, in the parish of East Baton Rouge, State of Louisiana, have invented certain new and useful Improvements in Shade and Curtain Hangers; and I do hereby declare the following to be a full, clear, and exact description of the invention, such as will enable others skilled in the art to which it appertains to make and use the same.

This invention relates to new and useful improvements in shade and curtain hangers, and particularly to devices of this character which are adapted to fit any window frame.

One object of the present invention is to provide a novel and improved device of this character in which the shade and curtain are suspended on a single structure which is capable of vertical and lateral adjustment so that the said structure may be fitted to windows of different widths, and the shade and curtain raised or lowered as desired.

Other objects and advantages will be apparent from the following description when taken in connection with the accompanying drawing.

In the drawing:

Figure 1 is an elevation of the device in proper position on the window frame.

Fig. 2 is a top plan view of the device, showing the manner of mounting the folding curtain supporting bracket arms.

Fig. 3 is an enlarged vertical sectional view taken on the staggered sectional line 2—2 of Fig. 1, to show the means for supporting the device at the top of the window frame, and the vertical adjusting means.

Fig. 4 is an enlarged horizontal sectional view taken on the line 4—4 of Fig. 1, showing one of the arrangements of one of the bifurcated members 25 with relation to one of the vertical rods.

Referring particularly to the accompanying drawing, 10 and 11 represent a pair of vertical bars or rods which are disposed in front of the side stiles of the window frame, the lower ends of said rods being threaded to receive the winged nuts 12. Bifurcated brackets 13 are secured to the side stiles and receive said lower ends of the rods 10

and 11, the nuts serving to hold said rod ends within the bifurcations.

Secured to the outer face of the heading 14, of the window frame, are the angle brackets 15, the outer ends of the horizontal portions of which are turned downwardly and then upwardly, as at 16, to form hooks, as clearly seen in the drawing. A sectional longitudinally adjustable bar 17 has its ends connected to the upper ends of the rods 10 and 11, by means of the bolts 18, winged nuts being engaged on the bolts to hold the parts together. Also engaged on the bolts, between the rods and the ends of the bar 17, are the inner ends of the curtain pole supporting arms 19, these arms being formed to extend outwardly from the front of the window frame, and laterally, as shown in the drawing, so that the curtain on the pole will completely cover the side stiles of the window frame. A second sectional and longitudinally adjustable bar 20 disposed below the first one is disposed behind the upper ends of the rods 10 and 11. Short plates 21 are disposed inwardly of the bars 10 and 11, and are secured in spaced relation to the ends of the bar 20 by the sleeves 22 through which pass the clamping bolts 23. Secured to and depending from the bar 20 are the brackets 24 which are arranged to receive the pintle ends of a shade roller. Bifurcated members 25 have their legs disposed in straddling relation to the rods 10 and 11 and the ends of said legs are movably supported on the ends of the rivets or bolts 26 which are engaged through the outer ends of the bar 20 and the short plates 21. The other end of each bifurcated member 25 has a rod 10' or 11' passed vertically through it, nuts 27 being engaged on the rods, above and below the members 25 to hold the parts in their proper relative positions. The upper portions of the rods 10' and 11' pass between the bar 20 and plates 21 and have nuts 28 engaged on their upper ends, while coil springs 31 encircle the rods and bear with their ends against the upper of the nuts 27 and the lower edges of the bar 20 and the plates 21. These rods 10' and 11' extend downwardly, inwardly of the bars 10 and 11 within convenient reach for proper manipulation, as will be more particularly referred to later herein. On the said bolts or rivets 26, between the

bar 20 and plates 21, are rotatably supported the grooved rollers 29 which bear against the rods 10 and 11 during the upward and downward movements of the bar 20.

5 The bight portions of the members 25 are thrown into frictional engagement with the inner portions of the bars 10 and 11 and engage in notches 30 formed in said bars, by the action of the springs 31.

10 It will be noted that the lower edge of the upper bar 17 is received in the hooks of the brackets 15, and that the lower ends of the bars 10 and 11 are supported in the brackets 13, whereby the entire shade and curtain hanger is properly supported on the window frame.

15 Attention is also called to the fact that the curtain supporting arms are foldable onto the upper edge of the upper bar 17, so that 20 the entire device can be easily and compactly folded for shipping.

20 When the rods 10' and 11' are lifted the springs 31 will be compressed against the bar 20 and plates 21, and the bifurcated 25 members 25 rocked out of engagement within the notches of the rods 10 and 11, thus permitting said rods 10' and 11'; together with the bar 20 and the shade and curtain supported thereon, to be raised or 30 lowered to the desired position on the window frame. It is sometimes desirable to permit air to enter the room when the upper sash of the window is lowered, but in the use of the present permanently attached 35 shade and curtain brackets, the air must strike the shade and travel down to the middle of the window, or thereabout, before entering the room. With the present device,

the shade can be lowered bodily thus permitting the air to pass freely over the shade 40 roller.

What is claimed is:

1. A shade and curtain hanger including parallel supporting members, a member vertically adjustable thereon, shade supporting 45 means on the adjustable member, foldable curtain pole supporting means on the upper ends of the parallel members, and means for holding the adjustable member at different points on the parallel members. 50

2. A shade and curtain hanger including vertical parallel bars having notches in their inner vertical edge portions, hook members carried by the upper portion of the window frame, a transverse bar carried by and spacing the upper ends of said rods and engaged in supporting relation in the hook members, means on the lower portion of the window frame for detachably holding the lower ends of said bars, a transverse member 60 slidable on the said bars, vertical rods slidably engaged with the transverse bar, bifurcated members straddling the first bars and having the ends engaged respectively with the transverse bar and with the last-named vertical rods, springs on the last-named rods between the bifurcated members and the transverse bar, and rollers on the ends of the transverse bar engaging with the first-named vertical rods. 65 70

In testimony whereof I affix my signature, in the presence of two witnesses.

DAVID J. DORSEY.
